[57] CLAIM

The ornamental design for an insulated container, as shown and described.

DESCRIPTION

FIG. 1 is a front elevational view of an insulated container, showing my new design, the rear view being a mirror image thereof;

FIG. 2 is a top plan view thereof; and

FIG. 3 is a side elevational view thereof, the opposite side being a mirror image thereof.

The undisclosed rear elevational view of the insulated container is a mirror-image of FIG. 1.

The undisclosed side view of the insulated container is a mirror-image of FIG. 3.

The undisclosed bottom plan view of the insulated container is plain and unornamented.

Fig. 1
